FOREIGN PATENT DOCUMENTS

CN 201005349 1/2008

Primary Examiner — Mary Ann Calabrese*Assistant Examiner* — Sloan Rozin(74) *Attorney, Agent, or Firm* — Warner Norcross + Judd LLP(57) **CLAIM**

The ornamental design for a hospital bassinet, as shown and described.

DESCRIPTION

FIG. 1 is a front perspective view of a hospital bassinet of the present disclosure;

FIG. 2 is a front elevational view of the hospital bassinet of FIG. 1, a rear elevational view is a mirror image of this illustrated view; and,

FIG. 3 is a first side elevational view of the hospital bassinet of FIG. 1, the opposing side elevational view of the hospital bassinet is a mirror image of this illustrated view.

The broken line showing of elements on the hospital bassinet illustrate portions of the article that form no part of the claimed design.

1 Claim, 3 Drawing Sheets(56)
